(57) **CLAIM**

The ornamental design for a storage bag for solar panels, as shown and described.

DESCRIPTION

FIG. 1 is a perspective view of a storage bag for solar panels embodying my new design;

FIG. 2 is a front elevation view thereof;

FIG. 3 is a rear elevation view thereof;

FIG. 4 is an enlarged left side elevation view thereof;

FIG. 5 is an enlarged right side elevation view thereof;

FIG. 6 is a top plan view thereof;

FIG. 7 is a bottom plan view thereof;

FIG. 8 is an enlarged view of the selected portion 8 in FIG. 1;

FIG. 9 is an enlarged view of the selected portion 9 in FIG. 4;

FIG. 10 is an enlarged view of the selected portion 10 in FIG. 7; and,

FIG. 11 is an enlarged view of the selected portion 11 in FIG. 7.

The broken lines shown in the figures depict portions of the storage bag for solar panels that form no part of the claimed design. The dash-dot broken lines in the figures are demarcating enlarged areas and form no part of the claimed design.
